V-BOAT

Anton Gasparich, Oakland, Calif.

Application July 29, 1940, Serial No. 348,192

3 Claims. (Cl. 9—6)

My invention relates to new and useful improvements in boat hull constructions.

An important object of my invention is the provision of a hull construction having a V-type bottom or keel section that is strong and compact and which permits a maximum number of straight pieces to be employed in the development of the hull in a manner to expedite and simplify the building of the same.

Another object of my invention is the provision of a hull construction of the above-mentioned character wherein the side and keel sections of the hull are joined in a rigid and durable manner and wherein the formation of the chine-pieces effecting the above juncture of the sections is unique to assure a water-tight union therebetween.

Other objects and advantages of my invention will be apparent during the course of the following description.

In the drawings, forming a part of this specification, and wherein like numerals are employed to designate like parts throughout the same,

Figure 1 is a top plan view of a boat hull constructed in accordance with the present invention,

Figure 2 is a side elevation thereof, and showing parts broken away,

Figure 3 is a fragmentary perspective view illustrating the manner in which the side ribs and planking of the hull are associated with the chine-pieces,

Figure 4 is a transverse sectional view taken on the line 4—4 of Figure 1,

Figure 5 is a top plan view of the hull framework,

Figure 6 is an enlarged fragmentary transverse sectional view of the hull, and

Figure 7 is an enlarged fragmentary transverse sectional view of a modification of the chine-pieces.

In the accompanying drawings, wherein for the purpose of illustration, is shown a preferred embodiment of my invention, the numeral 10 designates a boat hull, in its entirety, constructed in accordance with the present invention. As illustrated in Figure 4, the bottom 11 of the hull slopes upwardly from the opposite sides of the keel 12 and the side panels 13 incline slightly outwardly and upwardly from the edges of the bottom section. In plan, the hull here illustrated is provided with a transverse stern 14; the side panels 13 curve outwardly from the stern board to substantially the middle of the hull and, from

the middle of the hull, the side panels curve inwardly to join at the bow 15.

In the construction of the bottom of the hull, the keel 12 comprises a single timber which extends the full length of the hull along its longitudinal center and the transverse rib elements 16 are secured to the upper face of the keel at spaced intervals along its length. The ribs 16 are essentially V-shaped in elevation and the middle portions 17 thereof are flattened to properly receive the upper surface of the keel. The ribs are of gradually increasing length from the stern to substantially the middle of the keel, from which point they gradually diminish in length to provide the plan shape hereinabove described.

The side panels 13 include a plurality of spaced longitudinally bowed ribs 18, one vertical rib 18 being preferably provided for each end of each of the ribs 16. The present construction contemplates an arrangement wherein the ribs 18 will be disposed in slightly obtuse angular relation with the ribs 16 and the chine-pieces 19 join the outer and lower ends 20 and 21 of the ribs 16 and 18, respectively.

The chine-pieces extend for the full length of the hull at the juncture of the bottom section with the side sections and the formation of the same is unique to permit the above sections to be rigidly and strongly connected. The unique formation of the chine-pieces also permits the planking 22 applied to the bottom ribs and the planking 23 applied to the side ribs to be arranged therewith in a manner to provide a water-tight union therebetween and in a manner to provide a neat continuous outer surface of the hull.

Figure 6 illustrates the unique cross-sectional formation of chine-pieces particularly adapted for use with large boats. The opposite sides of each of the chine-pieces are provided with V-shaped grooves 25 the upper and lower walls 26 and 27 of which are arranged at right angles to each other. The lower walls, by reason of the fact that the side sections or panels are inclined outwardly and upwardly from the bottom section, are arranged in inwardly convergent relation to each other whereby the connecting ends of the ribs will abut the lower walls 27 of the grooves and extend at right angles therefrom to provide a strong, rigid construction. The manner in which all of the ribs abut the lower walls 27 of the grooves and extend at right angles therefrom positions the upper face 26 in overlapping pressed engagement with the inner surfaces of the connecting ends 20 and 21 of the ribs to provide a

water-tight joint and to further support and strengthen the construction.

The paneling 28 may be applied to the inner faces of the ribs 18 to finish the interior of the hull and the flooring 29 is secured to the transverse joists 30 which in turn are supported by the longitudinally extending stringers 31. Seats 32 are provided within the boat, in the manner clearly illustrated in Figures 1 and 4, and the air tanks 33 are arranged within the hull and below the seats to prevent the boat from sinking in the event that the same should capsize. The cushion rails 34 project outwardly from the sides of the boat below the gunwales 35 in the conventional manner.

Figure 3 illustrates a modification of the chine-piece construction, which modification may be used on any size of boat construction but is preferably employed in boat constructions which are slightly larger than those constructions which employ the chine-piece formation illustrated in Figure 6. The upper wall 26 of each of the grooves 25 is provided at spaced intervals along its length with recesses 36 which snugly receive the connecting ends of the bottom and side ribs. When the chine-pieces are constructed in this manner the ribs will be securely locked within the recesses and the planking, when applied to the ribs, will abut both the upper and lower faces 26 and 27 of the chine-pieces.

Figure 7 illustrates a further modification of the chine-piece which particularly adapts itself to small boat construction. Each of the longitudinally extending chine-pieces 19 is formed with an outer and a bottom face 37 and 38 which faces extend at an angle equal to the slope of the side and bottom sections of the hull. Each of the mentioned faces is provided with recesses at spaced intervals along its length, which recesses snugly receive the connecting ends 18 and 20 of the ribs of the side and bottom sections. The side planking 23 may then be applied directly to the outer faces of the ribs and to the face 37 of the chine-piece and the bottom planking 22 may be applied directly to the outer faces of the ribs 20 and to the face 38 of the chine-piece. The juncture of the faces 37 and 38 of the chine-piece 19 is preferably chamfered, as at 39, whereby the interfitting plank 40 may be fitted thereto in a manner to abut both the side planking 23 and bottom planking 22.

The chine-piece constructions here illustrated promote rigid and solidly constructed boat hulls and are particularly adapted, but in no wise restricted, to the V-type hull illustrated in the drawings. The cross-sectional formation of the chine-pieces may vary slightly as the angle between the side or bottom sections increases or decreases; however, such changes will be changes of degree and not of kind. Obviously, such other braces and retaining members as may be required may be incorporated in the construction, if desired.

It is to be understood that the form of my invention, herewith shown and described, is to be taken as a preferred example of the same,

and that various changes in the size, shape and arrangement of parts, may be resorted to without departing from the spirit of my invention, or scope of the appended claims.

- 5 Having thus described my invention, I claim:
1. In boat hull construction, a longitudinally extending keel member, a plurality of bottom ribs extending transversely of the keel member, a chine section extending longitudinally at each side of the hull and connected to the said ribs, the said chine section having a groove in its outer portion providing an upwardly extending exterior face and an outwardly directed face, the grooved portion of the chine section being shaped to provide a plurality of longitudinally spaced recesses along the upstanding face and set inwardly therefrom, a plurality of upstanding side ribs having their lower end portions fitted in the said recesses with their outer faces flush with the said upstanding face of each groove, and side planks fastened against the outer faces of the side ribs and the groove with the lowermost edge thereof resting on the outwardly projecting face of the groove.
- 20 2. In boat hull construction, a longitudinally extending keel section, a plurality of bottom ribs secured to and extending transversely of the keel section, the ribs at each side of the keel extending outwardly and upwardly from the keel, a chine section extending longitudinally at each side of the hull and connected to the outer ends of the said bottom ribs, the said chine section having a rabbet at its inner bottom portion and another rabbet at its upper outer portion, the inner rabbet of the chine providing a face perpendicular to the bottom ribs and against which the outer ends of the ribs abut and a transverse face against which the ribs are pressed, the outer rabbet of the chine having an outer upstanding face and an outwardly directed face with the upstanding face provided at spaced intervals with rectangular recesses, a plurality of upstanding side ribs having their lower end portions fitted in the said recesses with their outer faces flush with the upstanding face of the rabbet, and longitudinally extending planking secured against the outer faces of the side ribs and the rabbet with the bottom edge of the planking resting on the outwardly directed face of the upper rabbet in the chine.
- 30 3. In boat hull construction, a chine extending longitudinally of the hull at each side providing connection between the bottom and side structure of the hull comprising an elongated member of approximately rectangular cross section having a rabbet formed at the inner lower corner and in the outer upper corner, the said latter rabbet providing an upstanding exterior face and an outwardly directed face at right angles to the first mentioned face, the said chine being shaped to provide rectangular recesses at longitudinally spaced intervals indented from the upstanding face adapted to receive therein the lower portions of side ribs of the hull.

ANTON GASPARICH.
